COMPOSITE FIRE DOOR

Hubert W. Paul and Everett C. Shuman, Toledo,
Ohio, assignors to Owens-Illinois Glass Com-
pany, a corporation of Ohio

Application January 24, 1952, Serial No. 268,095

11 Claims. (Cl. 20—35)

1

Our invention relates to building construction units and particularly to an improved type of door, panel, or similar structure.

An object of the invention is to provide a structural unit such as a door or panel which is practically fireproof, being highly resistant to the destructive action of fire and extremely high temperatures. The unit is composed of a plurality of different materials each of which contributes to the fire resistance characteristics of the unit as a whole.

A further object of the invention is to provide a structural unit of the character indicated which is highly resistant to leakage or the passage therethrough of hot air, smoke or hot gases when bending or warpage of the unit is caused by exposure to very high temperatures, particularly to extreme heat concentrated on one side thereof, as in case of fire.

A further object of the invention is to provide a fireproof or fire-resistant unit composed of materials which are very light weight and highly resistant to heat and to the transmission thereof or leakage therethrough of hot air or gases when subjected to one sided pressure of such gases.

A further object of the invention is to provide a door, panel or structural unit which is fire-proof or fire-resistant upon exposure to flames and high temperatures for a prolonged period of time even though the veneer of such structures may be inherently non-fire-proof or non-fire-resistant.

Other objects of the invention will appear more fully hereinafter.

Referring to the accompanying drawings:

Fig. 1 is a face view of a structural unit for use as a door or panel embodying the present invention, portions of the surface material being broken away;

Fig. 2 is a part sectional edge elevational view of the unit with parts broken away;

Fig. 3 is a face view of the unit before the surfacing material has been applied;

Fig. 4 is a sectional view of the upper portion of the unit taken on the line 4—4 on Fig. 3;

Fig. 5 is a fragmentary face view of the unit in which the core sections are made of equal widths;

Fig. 6 is a fragmentary cross-sectional view showing adjoining core sections with flat butt-jointed heat surfaces with parts warped by heat; and

Fig. 7 is a similar view of our preferred construction wherein the adjoining edge faces of

2

the core sections are interlocked by tongue and groove construction.

This application is a continuation-in-part of our copending application Ser. No. 55,544, filed October 20, 1948, titled Composite Fire Doors.

Referring particularly to Fig. 3, the door unit is made up of a plurality of articulated core sections 10 and 11 mounted within a frame. The frame comprises thin flat sides 12 and ends 13 adhered together at their contacting edges 14. The frame members 12 and 13 are also adhered to the flat ends of the core sections 10 and 11.

The core sections 10 and 11 are preferably formed with interlocking tongues 15 and grooves 16 adapted to maintain a substantially air-tight or sealed joint between the sections and thereby prevent leakage or passage of hot air, gases or smoke particularly when the structure is subjected to very high temperatures on one side thereof sufficient to cause bending or warpage of the structure. The sections 10 and 11 may extend at any desired angle relative to the sides of the unit or frame, but in the preferred form, as shown, are at right angles thereto.

The core sections may comprise several sections 10b, 11b, extending across the width of the door as shown in Figs. 3 and 4. The vertical adjoining edge faces of the sections include engaging tongues and grooves 15a, 16a in the same manner as the horizontal abutting edge faces.

By making the core of the door or panel of a number of articulated sections 10 and 11, the unit is permitted to yield under the influence of successive and non-uniformly applied heat, without the unit cracking, breaking or permitting the passage of hot air or gases. The adjoining edges of the sections 10 and 11 provide lines of weakness permitting expanding, bending, or warping of the unit as a whole without the liability of cracking open or breaking.

In addition, the over-all warpage of the unit is much less than if it were made in one solid piece. This is due to the freedom of each of the individual sections to warp or bend individually of the others under the action of heat as herein-after described. Thus, the extreme corners of the unit will be more nearly in the original plane after exposure to high temperatures for a long period of time than if the unit were made in one piece.

The tongue and groove construction provides a much more effective and reliable seal between the adjoining edges of the core sections than

a structure such as shown in Fig. 6 wherein the edge surfaces 17 are plane surfaces making a flat butt joint. A slight clearance may be provided between the tongues and grooves as shown in Fig. 4 thereby avoiding any danger of breakage. If warpage or bending occurs, the adjoining surfaces, as shown at 18 in Fig. 7, will provide a close joint thereby preventing leakage. When such warpage is excessive, a certain amount of crumbling of the surfaces of the tongues and grooves may take place. This spalling is without detriment to the structure which still maintains a substantially air-tight, gas-proof joint. Some of the sections of the core or body, viz., the sections 11, are made narrow to permit a comparatively large number to be used thereby increasing the permissible extent of warpage or bending under excessive heat and at the same time decreasing the over-all warpage of the unit as a whole.

Fig. 5 shows a modification in which the core is made up of sections 11a all of substantially the same width.

The core or body of the panel consists of a light-weight, fire-proof material, preferably hydrous calcium silicate with a spiculated asbestos fiber binder. Such a material is now on the market under the trade name Kaylo and is disclosed in the patent of Lewis H. D. Fraser, No. 2,469,379, entitled "Heat Insulating Materials and Method of Making," issued May 10, 1949.

The frame 12, 13 may consist of wood or other material which will react, when exposed to high temperatures, in the manner presently described. If wood is used, it should be treated with a fire-proofing agent such, for example, as the material now on the market under the trade name Protexol.

A veneer or laminate is adhered to the major faces of the door or panel. The veneer or laminate may consist of any organic or inorganic material which can be adhered to the core of the door and which itself is not necessarily capable of withstanding prolonged exposure to high temperatures and flame. Such materials as wood, which is burned away; glass or ceramics which are broken away; and aluminum or copper which are melted away by the action of high temperature and flames may be used as the veneer for the panel.

In assembling the door or the panel shown in Fig. 1, the body or core 10 and 11 and the frame parts 12, 13 are adhered together by a layer of glue or adhesive material 19 covering all of the adjoining surfaces of the frame and core. Pressure and heat are then applied to a degree and for a sufficient length of time to eliminate the water content of the adhesive and/or set the adhesive. Thereafter, the sheets of veneer 21 are applied to the face of the panel or door. This veneer may be applied to both front and rear faces of the panel or door. A second or finishing veneer 22 may be applied over the veneer 21. The veneers are securely held in place by an adhesive, and heat and pressure are applied to set the adhesive. There is thus provided an integral composite unit forming a door or panel which is extremely light in weight, has high resistance to fire and high temperatures and which effectively prevents transmission of hot air or gases such as it may be subjected to in case of fire. The veneering gives a decorative finish to the exposed faces of the article.

When the door or unit is subjected to very high temperatures, as in case of a fire, the veneer

on the exposed face is disintegrated or destroyed, being burned, broken or melted away, dependent upon the material of which it is composed, and the flame then impinges directly against the core material. As action of the high temperature and flames continues, the restricting or binding action of the frame members 12 and 13 on the sections 10 and 11 is soon lost since the adhesive between the frame members and the sections progressively loses its effectiveness and the frame members may be charred upon being subjected to high temperatures for a period of time. However, the veneer and adhesive on the other side of the door are not affected by the flame and high temperatures due to the highly efficient fire resistance of the core material. Thus, after the door is subjected to the flame and high temperatures for a period of time, the sections are no longer restricted along the sides by the frame members and are held together by adhesive action to the veneer on the unexposed face.

After prolonged exposure to the flames, the individual sections 10 and 11 will begin to warp, resulting in over-all warpage of the door. The tongue and groove construction will prevent leakage or passage of hot air, gases or smoke between the sections 10 and 11. Since this construction also substantially lessens the overall warpage of the door, little or no leakage of hot air, gases or smoke will occur around the periphery of the door.

Modifications may be resorted to within the spirit and scope of our invention.

We claim:

1. An integral structural unit forming a door or panel, said unit comprising a core of inorganic, rigid, fire-proof, light weight material of a substantially uniform apparent density and consistency throughout, said core consisting of a plurality of articulated sections in the form of individual strips extending across said core and joined edge-to-edge, the adjoining edge surfaces thereof being formed with interlocking tongues and grooves fitted together and approximately in contact throughout their surface areas and forming an interlocking connection between the strips permitting a relative hinging movement of said strips when exposed to the warping action of excessive heat or fire applied to one surface only of said body while maintaining a substantially tight seal between the strips and preventing the leakage of air or gases therebetween when such relative movement occurs, said unit including a frame of material treated with a fire-proofing agent comprising members extending along the marginal edges of said core, said edges being flat and abutting said members, and adhesive material covering said marginal edges and bonding together the entire adjoining surfaces of said members, and a veneer covering and adhered to one major surface of the said core and frame and forming a finished surface.

2. The unit defined in claim 1, said unit including a second veneer covering and adhered to the other major surface of the said core and frame, whereby the said frame and one veneer hold the unit intact when the veneer on the opposite side of the unit is exposed to heat and flames by which it is burned away.

3. The unit set forth in claim 1, the material forming said core consisting of a hydrous calcium silicate.

4. An integral structural unit forming a door or panel, said unit comprising a core of inorganic, rigid, fire-proof, light-weight material of substantially uniform apparent density and con-

sistency throughout, said core consisting of a plurality of articulated sections in the form of strips joined edge-to-edge, the adjoining edge surfaces thereof being formed with interlocking tongues and grooves fitted together and approximately in contact throughout their surface areas thereby forming an interlocking connection between the strips permitting a relative hinging movement of said strips when exposed to the warping action of excessive heat or fire applied to one surface only of said body while maintaining a substantially tight seal between the strips and preventing the leakage of air or gases therebetween when such relative movement occurs, said unit including restraining means by which the said strips are rigidly held against relative movement, the restraining means comprising material destructible by high temperature, whereby the restraining action is lost by extended exposure of the unit to excessive heat or fire, the said restraining means consisting of a frame extending along the marginal edges of the core and rigidly united to said core, and a veneer adhered to and covering one major surface of the said core and frame.

5. The unit defined in claim 4, said unit including a second veneer adhered to and covering the other major surface of the said core and frame, whereby the first mentioned veneer holds the unit intact when the veneer on the opposite side of the unit is destroyed by the heat and flames to which it is exposed.

6. The unit set forth in claim 4, the material forming said core consisting of a hydrous calcium silicate.

7. The unit set forth in claim 4, said veneer being of a material subject to disintegration under applied high temperatures.

8. An integral structural unit forming a door or panel, said unit comprising a core of inorganic, rigid, fire-proof, light-weight material of substantially uniform apparent density and consistency throughout, said core consisting of a plurality of articulated sections in the form of strips joined edge-to-edge, the said strips having adjoining vertical and horizontal edge surfaces formed with interlocking tongues and grooves fitted together and approximately in contact throughout their surface areas thereby forming an interlocking connection between the strips

10

5

permitting a relative hinging movement of said strips when exposed to the warping action of excessive heat or fire applied to one surface only of said body while maintaining a substantially tight seal between the strips and preventing the leakage of air or gases therebetween when such relative movement occurs, said unit including restraining means by which the said strips are rigidly held against relative movement, the restraining means comprising material destructible by high temperature whereby the restraining action is lost by extended exposure of the unit to excessive heat or fire, the said restraining means consisting of a frame extending along the marginal edges of the core and united to said core, and a veneer covering and adhered to one major surface of the said core.

15

9. The unit defined in claim 8, said unit including a second veneer adhered to and covering the other major surface of the said core, whereby the said one veneer holds the unit intact when the veneer on the opposite side of the unit is removed by the heat and flames to which it is exposed.

20

10. The unit set forth in claim 8, the material forming said core consisting of a hydrous calcium silicate.

25

11. The unit set forth in claim 8, said frame being made of a material treated with a fire-proofing agent.
